[57] CLAIM

The ornamental design for a filter element, as shown and described.

DESCRIPTION

FIG. 1 is a top end view of a filter element embodying my new design;

FIG. 2 is a bottom end view of the filter element depicted in FIG. 1;

FIG. 3 is a front elevational view of the filter element depicted in FIG. 1;

FIG. 4 is a rear side elevational view of the filter element depicted in FIG. 1;

FIG. 5 is a left side elevational view of the filter element depicted in FIG. 1;

FIG. 6 is a right side elevational view of the filter element depicted in FIG. 1;

FIG. 7 is a top end view of a second embodiment of a filter element embodying my new design, the view being identical in appearance to FIG. 1;

FIG. 8 is a bottom end view of the filter element depicted in FIG. 7, the view being identical in appearance to FIG. 2;

FIG. 9 is a front elevational view of the filter element depicted in FIG. 7;

FIG. 10 is a rear side elevational view of the filter element depicted in FIG. 7;

FIG. 11 is a left side elevational view of the filter element depicted in FIG. 7; and,

FIG. 12 is a right side elevational view of the filter element depicted in FIG. 7.

The sole difference between the two embodiments resides in the sloped sides of the first embodiment.
